UNITED STATES PATENT OFFICE.

ROBERT B. COLEMAN, OF LOS ANGELES, CALIFORNIA.

MATERIAL-COMPRESSING MACHINE.

1,260,514.

Specification of Letters Patent. Patented Mar. 26, 1918.

Application filed August 5, 1916. Serial No. 113,363.

To all whom it may concern:

Be it known that I, ROBERT B. COLEMAN, a citizen of the United States, residing at Los Angeles, in the county of Los Angeles and State of California, have invented certain new and useful Improvements in Material-Compressing Machines, of which the following is a specification.

This invention relates to improvements in a material compressing machine, and particularly such as is adapted for the compressing of all kinds of comminuted material such for instance as sawdust, shavings, chips, straw, hay, feed pulp or the like, whereby such materials are brought into the form of sticks, blocks, briquets, etc. Sawdust, shavings, chips and the like when properly compressed form an excellent kind of fuel, thus utilizing materials which would ordinarily go to waste.

It is an object of the invention to produce a machine having ample power to tightly compress such materials as are above mentioned, means being provided for holding the materials until a proper length of stick or block has been formed, after which the stick is broken off and a binding means, such as wire, is twisted to hold the materials compressed and is cut off at the proper length.

It is also an object of the invention to provide a machine of this character in which the compressed material formed may be broken off and a binding wire fastened about the same, without the necessity of turning or twisting the separated sections of the compressed material, as has been necessary in devices for accomplishing such purposes heretofore.

It is a further object of the invention to provide a machine of the kind mentioned, in which a power plunger continuously forces and compresses the materials and in which stick dividing means is employed for causing the breaking off of the compressed materials at suitable intervals, a wire twisting and cutting means being provided and operated automatically by the compressing mechanism for twisting the wires between the severed portions of the compressed material, the fastening of the wire being accomplished in such a way that room is left therein to accommodate the expansion of the com-

pressed material, in the event of its becoming wet, without danger of breaking the binding wires.

With these and other objects in view the invention comprises certain novel constructions, combinations and arrangements of parts as will be hereinafter more fully described and claimed.

In the accompanying drawings:—

Fig. 1 is a front elevation of a machine constructed in accordance with this invention.

Fig. 2 is a vertical sectional view taken through the machine, from front to rear, portions of the mechanism being shown in side elevation.

Fig. 3 is a similar vertical sectional view through the frame of the mechanism the section being taken at right angles to the plane of the section in Fig. 2 and the parts being shown upon an enlarged scale.

Fig. 4 is a detail transverse sectional view upon an enlarged scale taken upon the line 4—4 of Fig. 2.

Fig. 5 is a similar sectional view showing the wire cutters, twisters and innermost portions ready to twist the wire and cut the same.

Fig. 6 is an enlarged detail fragmentary view showing the mechanism for receiving the stick of compressed materials after it has been forced from the die and is ready to be broken off.

Fig. 7 is a detail transverse sectional view taken upon the line 7—7 of Fig. 3.

Fig. 8 is an enlarged detail view showing the cam bar or member in front elevation.

Fig. 9 is a side elevation of the same, parts of the device being broken away and shown in section.

Fig. 10 is a detail view in elevation showing the reverse side of the cam portion of the member shown in Figs. 8 and 9.

Fig. 11 is an enlarged detail sectional view taken upon the line 11—11 of Fig. 2.

Fig. 12 is a perspective view of a stick of compressed material and showing the space within the twisted wires for permitting of the expansion of the materials compressed without danger to the wires.

The mechanism of the present invention is designed to compress loose or comminuted

2
 materials into composite solid form and especially materials that ordinarily would go to waste, such for instance as sawdust, shavings, chips and the like, or in fact any other materials which it may be desired to compress and bind in suitable form for various uses, and to pass a holding means around the compressed material to keep it in compressed form, the holding or binding means having sufficient slackness to permit of considerable expansion of the material under various conditions of atmosphere or under the different conditions of material when dry or wet. The mechanism is particularly well adapted for compressing materials of the character mentioned to form fuel from materials that would otherwise not be in proper condition for use in the ordinary stoves or furnaces. Thus the materials are preferably made into sticks or briquets of various sizes and shapes. In the accompanying drawings preferred embodiments of the invention have been disclosed and the details and features of the said invention will now be particularly described reference being had thereto.

In the said drawing, 12 indicates the main frame of the device having a transverse shelf or support 13 about midway of its height and a broad supporting base 14 at the bottom. The frame extends above the shelf 13 so as to form a standard 15 upon which is journaled a shaft bar 16 bearings 17 being provided therefor. The standard is preferably bifurcated at 18 and a large gear wheel 19 is secured to the shaft 16 so as to be revolvably mounted in the bifurcation. The gear 19 meshes with a pinion 20 which is carried by a power shaft 21. The said power shaft 40 extends to any suitable source of power and its rotation turns the pinion 20 and actuates the gear 19 in transmitting motion to the shaft 16. The shaft 16 projects at one end sufficiently far beyond the bearing 17 to have secured thereon a crank disk 22. The said disk 22 has a wrist pin 23 projecting therefrom which engages a pitman 24, the lower end of which is connected with a plunger head 25 moving in guide bars 26 secured to the side of the standard 15. The said head 25 has a depending compressing plunger 27 projecting therefrom and adapted to force loose materials into a die member 28 mounted upon the shelf portion 13 of the frame. The rotation of the shaft 16 by means of the gear 19 thus causes the vertical reciprocation of the compressing plunger 27 whereby sawdust or other loose material may be continually forced into and compressed within the said die 28.

The shelf 13 is provided with an opening 29 within which the die 28 is mounted. The upper part of said aperture is provided with an enlarged portion forming a die supporting shoulder 30. The die may be of any de-

sired construction but is preferably of such a nature that the materials may be compressed therein and the wires for binding the materials in compressed form, laid in grooves or kerfs in the sides of the composite 70 stick formed. The said die is preferably made in two sections, one of which is rigidly fastened to the shaft 13 by one or more screw bolts 31, passing through a flange 32 at the upper edge thereto. The other die section 75 is adapted to rock slightly in the opening 29, and is provided with a flange 33 tapered upon its under surface as clearly shown in Fig. 3. The aperture 29 is cut back slightly from its upper edge downwardly to permit the said section to rock when desired. The lower portion of the section is adjustably held with respect to the other section by means of an adjustable screw 34, the inner end of which bears 80 against a socket at 35 formed in the outer surface of the die section. By applying a lever handle 36 to the outer squared end of the screw bolt 34, the said bolt may be adjusted to permit the opening of the die sections to the extent desired. If it is found that the materials are held too tightly in the die, so as to be liable to become fastened or wedged therein, a slight turning of the screw bolt 34 will ease up upon the die section and 95 permit the materials to be forced on through the die. The lower end of the fixed die section is supported by an abutment bolt 37 for bracing the lower part of the die. The die sections are preferably provided with inner 100 sections 38 and 39 which are provided with shoulders 40 adapted to engage opposing shoulders 41 formed in the lower end of the die by the reduced bore thereof. Screws 42 hold the lining sections in place.

In order to properly lay the binding wires in the material as it is compressed elongated blades 43 are carried in the lining sections 38 and project inwardly from the surface thereof, a sufficient distance to embed themselves in the composite stick of material formed, whereby kerfs or grooves 44 will be formed in the stick 45 of composite materials. Wires 46 are introduced through apertures 47 near the lower ends of the die sections, the said wires being thus directed to the kerfs 44 by the lower ends of the blades 43. Below apertures 47 short blades 48 push the wires into the kerfs 44. The wires from opposite sides of the die are twisted together at 49 and thus extend across the end of the descending compressed stick and the said stick will push the wires along with it.

The repeated reciprocation of the compressing plunger 27 operates to force a compressed stick through the die and out of the lower end thereof. The said stick enters the upper end of a gripping and separating mechanism which consists preferably of an opposed pair of semi-cylindrical jaws 50 130

which are preferably pivoted together at their lower ends as at 51. The lower ends of said jaws 50 are movably held in proper position by a bearing 52 formed in a cross bar or plate 53 carried by the base 14 of the machine. The said jaws are loose in the bearing 52 to permit the jaws to move freely up and down and to separate slightly when the jaws are to be opened. The upper ends 10 of said jaws are provided with inturned gripping edges or flanges 54, the inner edges of which are usually serrated to form gripping projections or points as at 55. When the jaws are drawn together about the stick of materials compressed in the die, the flanges 54 will grip the stick and embed themselves in the material thereof, so that when the jaws are lowered they will cause the breaking of the stick at the point of engagement with the flanges 54 and the broken section will be pulled downwardly. The broken section is carried downwardly a suitable distance to permit of the twisting of the wires 46 between the severed portions of the 20 composite stick. The downward movement of the jaws 50 is usually limited by an adjustable stop 56 carried by one of the jaws and having a slot 57 engaged by a clamping bolt 58, which passes through said slot. The 25 desired space between the broken sections of the composite stick may be controlled by the adjustment of the said stop 56.

The jaws 50 are adapted to be raised and lowered at the proper time by means of a bifurcated lever 59 which is pivoted upon a cross rod or shaft 60 mounted at its ends in standards 61 of the frame 12. The inner bifurcated portion of the lever 59 is made of suitable width to receive the jaws 50 and is 30 pivotally connected with the said jaws by means of toggle links 62 as at 63. The links are movably mounted on the outer ends of bars 64 which are riveted or otherwise fastened to the said jaws 50. The links 62 extend beyond their pivotal connection with the lever 59 and their projecting end portions are preferably connected by springs 65, the action of the springs being to tend to fold the links 62 and draw the jaws 50 together. 35 This action however is controlled by the position of the lever 59 and when the inner end of the said lever is depressed it will move the links 62 downwardly, causing them to pull the jaws 50 together. When the bifurcated portion of the said lever 59 is raised again it will force the toggle levers 62 to move the jaws apart, a proper distance to release the composite stick from the gripping flanges 54. The outer end of the bifurcated lever 59 is provided with an angular slotted portion 66 which engages by means of its slot 67 a pin 68 which projects from one side of a vertically moving cam member or rod 69. The cam rod 69 is movable up 40 and down in the machine in conjunction with

the reciprocations of the plunger head 25. The said cam rod is not continuously moving however but is only brought into engagement with the said plunger head when it is desired to break off a section of the composite stick. The plunger head 25 carries a rod actuating arm 70 which projects past the rod 69 upon one side thereof so as to be then engaged by a pivoted latch 71 connected by links 72 with said rod. The said latch 75 70 is normally held out of the path of the arm 70 by means of a trip lever 73 pivotally mounted at 74 upon one side of the cam rod 69. The upper end of said trip lever is turned so as to project laterally and engage 80 a hole or aperture 75 formed in an arm 76 projecting from the latch member 71. A spring 77 fastened to the outer end of the arm 76 and connected with a pin or bolt 78 upon one side of the rod 69 tends to throw 85 the latch 71 outwardly and into the path of the arm 70 when the latch is released by the trip lever 73. The arm 70 is also adapted to engage a bracket or stop member 79 projecting from one side of the rod 69 as will 90 be clearly apparent by reference to Figs. 8 and 9 of the drawing. The rod 69 is carried to the lower end of its stroke by the action of the arm 70 against the stop 79. The said rod will not be elevated again until the latch 95 member 71 is released and it is thrown outwardly into the path of the arm 70. Upon the next depression of the arm 70 the latch member 71 will snap over the upper edge thereof and the upward movement of the 100 arm 70 will carry the rod 69 upwardly and then downwardly again. While at the upper end of its stroke the latch member 71 will be pressed inwardly by a spring actuated bolt or plunger 80, carried by a housing 81 which is supported upon a bracket 82 projecting from the frame of the machine. When the said latch member 71 is pressed inwardly the trip lever will again 105 engage the apertures 75 for holding the 110 latch member 71 in its normally folded position. The trip lever 73 is moved by means of a bar 83 pivotally connected at 84 with its lower end. The said bar projects from the cam rod 69 toward the gripping jaws and 115 extends through a slot 85 in one of the jaws 50. This end of the bar 83 is provided with a triangular portion or head having an inclined edge or face 86 extending into the path of the composite stick of compressed 120 materials which descends through the said jaws 50. When the stick has attained the proper length for breaking it off it will push the head to one side moving the rod 83 and the trip lever 73 so as to release the said 125 latch member 71. The inner end of the rod or bar 83 is movably supported by a link 87 which is pivoted at its lower end to said bar and at its upper end to a pair of projecting flanges 88 which extend from the jaws 50 on 130

each side of the slot 85 as clearly shown in Figs. 3 and 9 of the drawing. A pin 89 supporting the upper end of the link 87 may be adjusted to different heights by inserting it 5 through any one of a series of holes 90 formed in the said flanges 88. The length of the broken sections of composite material may thus be modified and controlled. A spring 91 connecting the rod or bar 83 with the jaw 50 normally pulls the said bar inwardly and holds the trip lever in latch locking position until the stick of compressed materials has attained a suitable length to force the bar 83 outwardly against the action of the spring 91.

The shape of the angular slot 67 in the lever 59 is such that when the cam rod 69 is in its normally lowered position the weight of the jaws 50 cannot depress the said jaws 20 farther for a recess 92 formed in the lower end of the slot 67 is made of suitable depth to form a shoulder at 93 which must prevent the said lever from rising at its outer end until the pin 68 has been raised 25 by the upward movement of the rod 69 as will be readily understood by reference to Figs. 2 and 9 of the drawing. As soon as the pin engages the inclined surface 94 of the angular slot it will begin to raise 30 the lever 59 and throw the lower end thereof outwardly for a short distance or until the jaws 50 have lowered the broken off stick section sufficiently to fasten the wires about the same. The remainder of the angular 35 slot 67 will then be in approximately a vertical position so that the rod 69 with the pin 68 may continue to move upwardly to their full strokes without further moving the jaws 50. Upon the depression of the cam bar 69 40 again to the lower end of its stroke the pin 68 will lower the lever 59, raising and opening the jaws 50, and the said shoulder 93 will be brought into position once more to chock the lever in position to hold the jaws 50 in readiness for another stick section.

The cam rod 69, is preferably prevented from moving without the positive action of the arm 70 and for this reason is passed near its lower end between a pair of spring bars 50 which have friction pads or bases 96 secured upon their inner surface and adapted to grip the cam bar 69 between them. The tension of the bars 95 may be controlled by a bolt 97 connecting their free ends as clearly 55 shown in Fig. 11. The gripping of the bar 69 by this mechanism is such that the said bar will remain in any position at which it may be moved by an arm 70, whereby the movements described will be made possible.

60 An important feature of this invention is that the binding wires which are pressed around the composite sticks formed in the machine may be twisted with sufficient slack to prevent their being snapped or broken 65 when the materials expand for any reason.

This frequently happens if the wires are too tight and the compressed materials become moist or wet in any way. The twisting of the wires is accomplished by means of coöperating twisting and cutting members 70 96 and 97 which are mounted upon a plate or platform 98 arranged and movably supported near the upper end of the jaws 50. The plate 98 is provided with guide recesses 99 and 100 formed in its surface and suitable 75 actuating pins may project downwardly from the said members 96 and 97 so as to be engaged by a suitable mechanism for drawing the pins toward and away from each other. The plate 98 is journaled in a recess 80 102 formed in a cross bar or platform 103 which is supported below the shelf 13 between the standards 61. The said plate 98 has a sleeve portion 104 which extends through the aperture 102 and sufficiently 85 below the same to receive and have rigidly fastened to the lower end thereof a beveled gear 105. The beveled gear meshes with an actuated pinion 106 mounted upon a short 90 shaft 107. The shaft 107 is journaled in the standard 61 and is adapted to be rotated by a bevel gear 108 which meshes with a bevel gear 109 carried by the lower end of an inclined shaft 110 mounted upon suitable 95 brackets on the main frame of the machine. The upper end has secured thereto a bevel gear 111 which meshes with an actuating bevel gear 112 secured upon a shaft 21. By this connection of gears and shafting the plate 98 is given continuous rotation when 100 the machine is in operation so that the members 96 and 97 are carried around the upper ends of the jaws 50 continuously.

The pins 101 which control the movement of the cutter and twister carry members 96 105 and 97 depend from the lower sides of said members and normally engage a groove 113 formed in the upper face of the platform 103. The said groove 113 is preferably circular so that ordinarily when the plate 98 110 is rotating the members 96 and 97 will remain in their outer positions. The inner wall of the groove 113 is however broken at intervals forming gaps or passage ways 114 on opposite sides of the said groove 113. 115 An inner groove 115 is also formed in the said platform 103 and is connected by the passages 114 with the outer groove 113. Switch members 116 are pivoted at 117 in the said passages 114 and their free ends 120 are so arranged that the switches may be thrown outwardly to the positions shown in Fig. 7 in which positions they will guide the pins 101 so as to carry them into the inner groove 115. When the switches 116 are 125 in the positions shown in full lines in Fig. 7, the pins 101 will be guided through the passages 114 to the outer groove 113 again. The switch members 116 are controlled by arms 118 which are axially connected with 130

the said switch members 116, and extend below the shelf 103. Links 119 connect the said arms 118 with a cross bar 120 which in turn is carried by the inner end of a 5 thrust rod 121. The said thrust rod engages a bearing 122 formed in a bracket 123 which depends from the shelf 13. The thrust rod 121 projects beyond the cam rod 69 a sufficient distance to have a pin 124 10 which is carried by said rod engage a cam mechanism 125 upon the said cam rod 69. The said cam mechanism comprises a part with guide flanges 126 and 127 formed upon one face of the device the flange 127 being 15 broken away at intervals a sufficient distance to receive a movable cam or switch member 128. Said cam is pivoted at 129 and its opposite ends are curved in opposite directions with respect to each other forming a 20 substantially S-shaped cam. Pins 130 project through curved slots 131 in the base of the cam mechanism and sufficiently beyond the same to be engaged by springs 132 which are riveted at their outer ends as at 133 to 25 the said base plate. Stop projections 134 keep the springs normally pressed against the said pins 130 as clearly shown in Fig. 10. The action of the springs is such that the cam 128 normally occupies the position 30 shown in Fig. 9 of the drawing, but its ends may be pushed aside by the pin 124 at certain points in the operation of the cam mechanism. With the parts in the position shown in Fig. 9, when the cam bar 69 rises 35 the pin 124 will be carried inwardly by the cam 128 and will cause the throwing of the switch members 116 outwardly. The said pin will move the cam 128 at its lower end so as to snap by the same when the cam bar 40 69 has been elevated, to its full height. Upon the descent of the said cam bar the cam 128 will force the pin 124 into the outer part of the cam device, whereby the thrust rod 121 is drawn outwardly again and the 45 switch members 116 are swung inwardly to their normal position.

The cutter carrying members 96 and 97 are formed with curved recesses at their inner ends of greater width than the width of 50 the wires 46 before they have been twisted. The curved portions 135 of said recess are of such shape that when the members 96 and 97 are carried toward each other by the drawing of the pins 101 into the inner 55 groove 115, that the wires will be drawn together between the severed sections of the composite stick until they engage the reduced shanks 136 of cutters 137 which project from the middle portion of said recess. 60 The members 96 and 97 being arranged one about the other will slide upon each other and the wires will be drawn together as shown in Fig. 5. With merely the shanks 136 of the cutters between them the rotation of the platform 98 when the wires are

in this position causes the wires operated to be twisted between the broken ends of the compressed stick. The cutters have cutting edges 138 upon the inner sides of their cutter heads 137, and when the said cutters are 70 drawn apart by the pins 101 moving to the outer groove 113 the cutters will have a shearing action upon the said wires and cut them off. Since the shanks of the cutters were rotated to twist the wires, the twisted 75 portions will be of the same length upon each side of their cut ends. Half of the twisting portion will complete the binding and securing of the wires about the broken off section of the stick and one half will 80 hold the wires, which receive the lower end of the stick coming from the dies, together ready for the binding of the next section of the stick. The cutters being centrally located are also in position for the wires to be 85 drawn together upon each side thereof so that the rotation of the cutters will twist the wires. The movement of the knives inwardly will only be caused when the composite stick has reached the desired length 90 and the cam bar 69 has been elevated for accomplishing its various functions. The wires are usually carried by spools 139 pivoted upon the frame of the machine at any desired point so that the wires can be freely 95 drawn therefrom into the dies through apertures, 47.

In the operation of the machine the plunger 24 reciprocates continually. Material is fed in any desired manner to the die 28, a 100 flaring hopper 140 mounted upon the upper end thereof facilitating the operation. Under the continued reciprocation of the plunger the materials will be forced into the die and compressed into an elongated stick of 105 substantially the shape shown in Fig. 12. In being forced through the dies, the wires will be laid in the kerfs 44 and then carried on downwardly between the gripping jaws 50. As soon as the lower end of the composite stick strikes the inner end of the bar 83 the trip lever will be operated for releasing the latch 71 whereby the said latch will engage the arm 70 and the cam bar 69 will be elevated and depressed again for causing the depression of the jaws 50 in breaking off the lower end of the stick, and the operation of the wire twisting and cutting knives to sever the wires after they have been fastened about the upper end of the stick. 110 By making the jaws 50 descend a considerable distance the wires can be twisted so as to leave a slack space at 141 within the upper twisted end thereof as shown in Fig. 12. This space may be made sufficient 115 to accommodate all swelling or expansion of the compressed materials and thus prevent a snapping of the wires. The materials thus compressed and bound up form an excellent 120 fuel and the wires hold the fuel together so 125 130

that it does not fall apart and separate, while burning. The wires are prevented from breaking in the fire too quickly by reason of their being embedded for the most part in the kerfs of the stick. The embedding of the wires in the said kerfs is chiefly needed, however, for preventing the materials from curling out from under the wires as the sticks are burned.

10 The power shaft 21 is preferably capable of connection with a source of energy by means of any ordinary clutch mechanism as 5 142 which bears against the sides of a pulley 143 mounted upon the shaft 21. A belt 144 extends from the pulley to any suitable 15 source of power, not shown. The clutch mechanism is carried upon the shaft 21 and may be thrown into or out of pulley gripping position by a hand lever 145.

20 It will be evident that many minor details 25 of the device may be considerably altered within the scope of this invention and that mechanical equivalents may be substituted for some of the parts without departing in the least from the spirit of the present invention.

In machines of this character, as heretofore constructed, in twisting and fastening the wires between the stick sections, it frequently happens that both wires will not be 30 twisted, but one will be twisted around the other, so that an insecure fastening results and the wire which is not twisted will slip out of the other. This is not possible with 35 the wire twisting mechanism of the present machine, for the twisting shanks go between the wires as they are drawn together, and since such shanks are between the wires, one must be twisted just as much as the other. 40 Sometimes in other machines heretofore used also the compressed sticks did not break at the proper point. In the present machine the gripping jaws positively insure the 45 breaking of the sticks at the desired points and prevent the cutting of the wires at any but the right place.

What is claimed is:

1. A material compressing mechanism having a shaping die, a plunger adapted to 50 compress materials in the die, means for passing wires about the material compressed, means for breaking the compressed materials into sections, means for inclosing the materials in holding wires, and a revolving 55 knife device adapted to twist the wires between the sections and cut the wires.

2. A machine of the class described, the combination with mechanism for compressing materials into the form of a stick, and 60 means for laying wires about the same, of a mechanism for gripping and breaking off a portion of said stick, a cutting device adapted to engage said wires between the broken parts of the stick and means for 65 moving said cutting device around the axis

of the stick whereby the wires are twisted for fastening them and are cut between the sections.

3. A machine of the class described comprising a mechanism for producing a composite stick of compressed material, means for receiving a portion of said stick and breaking it from the remainder thereof, combined wire twisting and cutting devices adapted to be thrust between the severed 75 portions of the stick and binding wires around the section of the stick broken off, the said twisting and cutting devices being adapted to twist and sever the wires.

4. A machine of the class described having a shaping die, and means for forcing and compressing materials therein, means carried by the die for applying binding wires to the compressed materials, gripping jaws for engaging the composite stick 80 formed in the die and pulling a portion of the same away from the portion in the die, oppositely moving wire twisting and cutting devices having means for drawing the wires together and twisting the same, the 85 withdrawal of the twisting portions operating to cut the wires.

5. A machine of the class described having a compressing mechanism adapted to 95 form a composite stick with grooves in the sides thereof, means for placing material binding wires in said grooves, stick gripping means adapted to receive the composite 100 stick with the wires about the same, reciprocating cutters having twisting shanks and cutting heads and means for moving said cutters to cause the shanks to twist the wires and the heads to cut the same, whereby the bound portion of the material is severed from the other materials remaining in the 105 machine.

6. A machine of the class described having a material shaping and compressing mechanism and means for placing holding wires about the compressed materials, material receiving and breaking jaws having gripping edges at the point of breaking, means for lowering the said gripping jaws to break the compressed materials, oppositely moving wire cutters adapted to be 115 thrust between the wires for twisting them, the said cutters having cutting edges adapted to cut the wires as the cutters are withdrawn from between the sections of the compressed materials and means for controlling 120 the amount of movement in the said jaws, whereby a proper amount of slack will be left in the wires to accommodate any expansion of the materials within them.

7. A machine of the class described having a compressing and forming mechanism, means for placing binding wires about the material as it is compressed, gripping jaws for receiving a portion of the compressed materials, means for bringing the jaws to 125 130

gether on said materials and lowering the jaws for breaking off a section of the materials, wire cutting and twisting members having enlarged cutter heads behind which 5 the wires are twisted and whereby the withdrawal of the twisting members will cause the heads to sever the wires.

8. A mechanism of the class described comprising a shaping die, means for compressing materials therein, means for placing wires on each side of the composite stick formed by compressing said materials, a stick gripping mechanism adapted to break off and pull a section of the stick away from 10 the die, a rotating member surrounding the gripping member and having lapping reciprocating plates provided with concave inner edges capable of drawing the binding wires toward each other as the plates move 15 inwardly, shanks projecting from said plates and having cutter heads on their inner ends, means for rotating the member carrying said plates and twisting the wires and means for separating the plates for causing the cutter 20 heads to shear off the wires.

9. A mechanism of the class described comprising a gripping and shaping mechanism, means for applying binding wires around the materials compressed, a pair of 30 material gripping jaws pivoted together at their lower ends and having gripping edges at their upper ends adapted to define the line of breakage in the materials compressed, a lever for raising and lowering said gripping jaws, toggle members engaging said lever for closing or opening the said jaws under the action of the lever, the said lever having a cam slot, a cam carrying rod adapted to engage said slot for causing the lever 35 to raise and lower the toggle members and the mechanism carried thereby, and means for operating the cam carrying bar in conjunction with the movement of the compressing mechanism.

40 10. A machine of the class described comprising a material compressing plunger, a die, means for breaking the stick of compressed material below the die and separating the same from the die, rotating and reciprocating cutters adapted to be thrust between the wires below the die, means for bringing the cutters together and then separating them for cutting the wires as they are twisted, and a cam mechanism for actuating 45 the said cutters in correspondence with the movement of the said plunger.

11. A machine of the class described comprising a compressing plunger, a die, means for applying wires around the materials 50 compressed, a stick breaking mechanism, a lever for operating the same, means for limiting the depression of said breaking mechanism for controlling the space between the end of the die and point to which the broken off materials are carried, a wire twisting

and cutting mechanism adapted to engage the wires below the die, a reciprocating cam bar operated by the plunger, a thrust bar actuated by said cam member, for operating the twisting and cutting mechanism, a cam 70 plate carried by said cam bar and having means for engaging the lever which controls the material gripping and breaking devices and means upon the said bar for effecting its connection with the plunger.

75 12. A machine of the class described having mechanism for compressing materials into stick form, means for applying holding wires about the same, means for breaking off portions of the stick as it has been formed 80 and separating the same from the die, reciprocating cutters adapted to engage the said wires between the portions of stick, a cam member having guiding paths thereon, projections carried by the cutters and engaging said paths, means for directing the said projections from one path to the other, and means for rotating the knives about the wires to cause their twisting before they 85 are cut.

90 13. A mechanism of the class described comprising a material compressing and forming member, means for applying binding wires about the compressed material, a member for severing the material in desired 95 lengths, a rotating member having reciprocating cutters, a cam member having cam paths, the cutters having pins engaging said paths, switch members adapted to direct the pins from one path to another for reciprocating the cutters, a bar for throwing said switch members, a cam for reciprocating said bar, a cam carrying bar for imparting movement to said cam, and means for reciprocating said bar whereby the knives will 100 be caused to twist and cut the binding wires.

14. A mechanism of the class described comprising a die, a plunger for compressing materials into stick formed therein, a material gripping and breaking member for receiving the compressed materials from the die, a reciprocating bar having a latch device thereon, an actuated arm operated by said plunger and adapted to engage said latch mechanism for reciprocating the said 110 bar, a lever for raising and lowering the material breaking member and having a slot engaging the said bar, a trip lever for releasing said latch mechanism when the arm is to reciprocate the bar, a thrust bar connecting the trip lever for operating the inner end of said thrust bar having a portion projecting into the path of the broken off compressed material, whereby the material will 115 be broken off at the desired length, and a spring normally holding said bar in material engaging position.

15. A machine of the class described having a stick forming means, means for passing wires about the stick and means adapt- 130

- ed to be thrust between the wires, between sections of the sticks formed, for twisting the wires, and means for cutting the twisted wires.
- 5 16. A machine of the class described comprising means for forming a composite stick having wires passed around the same, means for separating portions of the composite stick formed, means adapted to be 10 thrust between the wires for twisting the same, said means also having cutting edges whereby the wires may be cut upon withdrawing the twisting means, and means for separating the said twisting and cutting 15 means.

17. A machine of the class described having a composite stick forming and shaping means adapted to apply binding wires to the sticks formed, means for separating one 20 portion of the stick formed from another portion, means for drawing the wires together between the broken sections of the stick, said means having cutters adapted to be thrust between the wires for twisting them the withdrawal of the knives operating 25 to cut the wires and a switch mechanism for throwing the cutting and twisting

means inwardly to perform their functions and outwardly again in return for another operation.

18. A machine of the class described having a composite member forming device, means for applying wires to members formed, means for separating the composite material into separate stick sections with 30 the binding wires extending from one to the other wire twisting and cutting means adapted to be thrust between the stick sections and between the wires for drawing the wires together and twisting them and then 35 cutting the wires and guiding means for directing the operation of the twisting and cutting members, switch devices for throwing said members into or out of twisting and cutting position and means extending 40 into the path of the composite members formed for controlling the length of the stick sections thereof.

In testimony whereof, I have hereunto set my hand, in presence of two witnesses.

ROBERT B. COLEMAN.

Witnesses:

ROSEBUD CARNES,
CASSELL SEVERANCE.
